UNITED STATES PATENT OFFICE.

WINFIELD H. YOST, OF MONTREAL, QUEBEC, CANADA.

DRAFT RIGGING.

Application filed June 7, 1920. Serial No. 386,974.

To all whom it may concern:

Be it known that I, WINFIELD H. Yost, a citizen of the United States, residing at Montreal, in the Province of Quebec and 5 Dominion of Canada, have invented certain new and useful Improvements in Draft Rigging, of which the following is a specification.

My invention relates to draft rigging, as 10 used on railroad cars, to cushion the shocks incidental to the movement of cars.

It is a well known fact that with the ordinary wedge or low velocity type of draft rigging the car will receive quite an initial 15 shock before the wedges will act, and that the action during the stroke will be very uneven, causing fast wear to both the draft rigging parts and the car. With the lever or high velocity type of draft rigging, the 20 action is so fast that it is impossible to get the high resistance necessary, although the action will be free of the initial shock and will be smooth during the stroke. In my invention I employ levers that will in- 25 stantly put the draft rigging in motion and wedges to start retarding the motion as soon as it starts. In this manner the action will be free from initial shocks and will be smooth throughout the stroke, at the same time having 30 a high absorbing capacity.

Owing to the limited travel of the coupler, it has been impossible heretofore to obtain a draft rigging of high capacity, work-absorbing power, and smooth action, and 35 consequently great damage has been done to cars and contents. To overcome this defect, I provide a mechanism in which a certain portion of the energy of the coupler is utilized to retard further movement of the 40 coupler. I preferably accomplish this by the novel combination of wedges and levers so arranged and adapted that forces applied to the mechanism will be transferred proportionately through the lever mecha- 45 nism to the wedge mechanism in such a manner that the forces on the fulcrum end of the lever, through its bearing on side wedge member, cause longitudinal and transverse movement of the side wedge member, bring- 50 ing frictional contact with the central wedging member proportionally as to the leverage. The central wedging member will travel independently in the same direction as the side wedges (compressing the spring) 55 relatively to coupler travel owing to the leverage of the lever member. During this

action the spring mechanism is used to keep contact of the different parts and for returning this mechanism to its normal release position. I attach a great deal of importance to the fact that the wedges 9 and frictional member 8 of the wedging mechanism move in the same direction and independently of each other. With this combination the reaction of the spring will instantly force 60 contact between the parts of the wedge mechanism with the start of motion. The spring has two distinct functions, first to start friction action by retarding the central member and second to release the entire 70 mechanism and to restore it to normal position.

It will be seen readily that with this combination of differential levers and wedges, a high capacity resistance mechanism is obtained irrespective of spring resistance, as the side wedge members will grip the center friction member as soon as movement of levers starts, and continued movement will cause a greater pressure of the side wedge 80 members on the central member, making a greater resistance to the movement of the central member. During this action the central member will travel a greater distance than the coupler and the main follower 85 through the medium of the levers. When the main follower reaches the end of the casing, all parts will be inside of the casing and any force greater than the absorbing capacity of the draft rigging will be taken directly on the casing. 90

One object of my invention is to provide a draft rigging in which a portion of the energy in the moving parts is used to create resisting power in the draft rigging. 95

Another object of my invention is to provide a draft rigging that will have frictional resisting travel through greater distance than the travel of the coupler. 100

Another object of my invention is to provide a draft rigging in which differential levers are used in combination with wedges and springs to increase the cushioning power of the resisting elements. 105

Another object of the invention is to produce a draft rigging in which all the moving parts are protected by an outer casing when the capacity has been reached; to prevent the springs from going solid; and to provide a self-adjusting means to take up 110 wear.

The objects of my invention are accom-

plished by the mechanism illustrated in the accompanying drawings, in which—

Figure 1 is a horizontal central section looking downwardly with the parts in release position;

Figure 2 is a longitudinal vertical section taken on line A—A of Figure 1, with the yoke elevation;

Figure 3 is a cross section taken on line 10 B—B of Figure 1;

Figure 4 is a view similar to Figure 1 with the parts in closed position;

Figure 5 is a detail perspective view of the casing showing some parts in section;

Figure 6 shows the levers in perspective;

Figure 7 is a perspective view of a side wedge;

Figure 8 is a perspective view of the central member, some parts being shown in section; and,

Figure 9 is a horizontal central sectional view of draft mechanism embodying a modification of my invention.

Draft members or sills 1 of the car are provided with draft lugs 2 and 3. The draft lugs are of the usual construction and spaced according to the standard practice for the application of the draft rigging, as clearly illustrated, and for the purpose hereinafter set forth. A member or casing 4 is provided, preferably having one end thereof open. The closed end bears on the draft lugs 3 and forms an abutment for a spring 5. Mounted within the casing 4 are the spring 5, follower 6, spring 7, central friction member 8, and two floating side wedges 9. Adjacent the open end of the casing 4 I mount a plurality of differential levers 10 in engagement with the floating wedges 9, central friction member 8, and the main follower 11, forming the complete mechanism. The draft rigging as above described may be encircled by the yoke 12, attached to the drawbar 13, in the usual manner.

It will be readily seen that under buffing stresses the drawbar 13 will move the main follower 11 inwardly and cause each lever 10 to rotate about its fulcrum point 10^a on its associated side wedge 9. Side wedge 9 in each case being in contact with casing 4, at the flared portion 4^a, tends to move inwardly both longitudinally and transversely, thus causing pressure to be applied to the central friction member 8.

At the same time the opposite end 10^b of each lever 10 will cause the central friction member 8 to move inwardly independently of the side wedges 9, compressing the springs 5 and 7, and slide along surface 9^a of each side wedge 9, creating friction.

As the lever 10 rotates, the point of contact 10^c with follower 11 moves toward the fulcrum point 10^a on side wedge 9, causing 65 the length of the lever arm to decrease,

while the point of contact 10^b between the lever 10 and central friction member 8 will move away from the fulcrum point 10^a on wedge 9, thus increasing the length of the lever arm. It will be seen that as the travel 70 of the drawbar increases inwardly, the leverage compressing the spring will decrease, making the travel of the springs 5 and 7 and central friction member 8 faster than the travel of the drawbar 13, giving a long 75 cushioning resistance. When the travel of the central friction member 8 and the movement of levers 10 continues until the follower 11 comes in contact with the outer end 4^b of the casing 4, Figure 4, then all the 80 stresses greater than the absorbing capacity of the moving parts will be taken through casing 4 to the rear draft lug 3.

As the leverage on the wedges 9 increases 85 during an inward movement of the follower 11, a greater proportion of the weight transmitted by the levers 10 will be placed on the side wedges 9, by part 10^a of levers 10, and cause the side wedges 9 to grip the frictional member 8 with a progressively 90 increasing resistance which will serve to retard inward movement of the part 10^b of the lever 10.

In releasing from a position shown in Figure 4, the stored energy of the springs 5 and 7 will force the side wedges 9, central friction member 8, levers 10 and the follower 11 back to normal position, as shown in Figure 1.

In pulling stresses the action will be the same as in buffing except that the main follower 11 will remain stationary while the yoke 12 will move the casing 4 forward, rotating the levers 10 in the same manner as above described.

In order to protect the spring 7 from under strains, and to prevent it from going solid, I provide the central friction member 8 with walls 8^b extending from the front wall 8^a and of such a depth that they will come in contact with follower 6 before spring 7 will become solid. In a like manner, I provide stop lugs 4^c on the casing 4 to stop movement of follower 6 at a point to prevent spring 5 from going solid. It is well known that the springs will not last long or give good service if they are continuously going solid. I also provide the central friction member 8 with flanges 8^e to support levers 10 (Figure 8).

To provide means for automatically taking up wear on the moving parts and to prevent looseness in my mechanism, I provide levers 10 of such a shape that they will rotate about their fulcrum points 10^a on the side wedges 9 and bearing part 10^b on the central friction member 8 during movement caused by the outward thrust of the springs 5 and 7 on account of the initial compression, allowing the central friction 125 130

member 8 to advance closer to the main follower 11 until the central friction member 8 will come in contact with part 10⁴ of lever 10. At this point the levers 10 should be replaced. It is well known that all friction mechanisms wear out in time and have to be replaced. However, with my construction the maximum amount of work may be done before replacement is required.

10 In Figure 9 I have disclosed a modification in which all parts are substantially the same, as hereinabove described, with the exception, however, that movable bearing members 40 are inserted between the inclined portions of the side wedges 9 and casing 4. This latter arrangement reduces friction where it is not needed and permits a more even application and withdrawal of friction between the wedges 9 and central member 8.

15 The general construction described in all figures of the drawings is simple, durable, compact, efficient in operation, easy to assemble and disassemble, and permits of the use of standard springs which are applied to cars.

20 It is my intention to cover all modifications of the invention falling within the spirit and scope of the following claims.

25 39 I claim:

1. A draft gear comprising a spring member, a friction member co-acting with said spring member, wedge mechanism acting upon said friction member to retard the movement of said friction member, means to hold the parts in operative engagement, and levers acting upon said friction member and said wedge mechanism through which levers both the friction member and wedge mechanism are moved independently of each other.

member and the wedge mechanism are moved.

11. In draft rigging for railroad cars, the combination of a draw-bar, a differential lever mechanism operatively associated therewith, a wedge mechanism, a friction member and a spring, said lever cooperating with the wedge mechanism and spring, and a part of said wedge mechanism coacting 10 with the friction member and movable independently thereof.

12. In draft rigging for railroad cars, the combination of a wedge member, coacting wedging means associated therewith, a friction member, said friction member having frictional engagement with and movable independently of the wedge member, a lever engaging with the wedge member and the friction member, and means for resisting the 20 motion of the parts and restoring them to expanded condition after compression.

13. In draft rigging for railroad cars, the combination of a wedge coacting wedging means associated therewith, a friction member in frictional engagement with the wedge, lever mechanism bearing at one end on the wedge and having the other end bearing on the friction member, and means for resisting the motion of the parts and restoring them to expanded condition after compression.

14. In draft rigging for railroad cars, the combination of a draw-bar, a wedge, coacting wedging means associated therewith, a friction member in engagement with the wedge, a lever operatively associated with the draw-bar and bearing on the wedge and on the friction member, and means for resisting the motion of the parts and restoring them to expanded condition after compression.

15. A draft gear comprising a spring member, a central friction member mounted upon said spring member, wedge mechanism co-acting with said central friction member to retard the movement of said central friction member, and differential levers mounted upon said central friction member and said wedge mechanism through which differential levers both the central member and the 50 wedge mechanism are moved.

16. In draft rigging for railroad cars, the combination of a wedge member, coacting wedging means associated therewith, a friction member cooperating with the wedge

member, and a lever adapted to bear on the wedge member and on the friction member, and a spring yieldingly resisting the movement of the friction member.

17. In draft rigging for railroad cars, the combination of a wedge member, coacting 60 wedging means associated therewith, a friction member in engagement with the wedge member, a lever adapted to bear on the wedge member and on the friction member, and a spring yieldingly resisting the movement of the lever.

18. In draft rigging for railroad cars, the combination of a casing, a friction member, a wedge in engagement with the casing and the friction member, a lever for causing relative motion between wedge and friction member, and means for resisting the motion of the parts and restoring them to expanded condition after compression.

19. In draft rigging for railroad cars, the 75 combination of a casing, a friction member, a wedge in engagement with the casing and the friction member, a lever bearing on the wedge and on the friction member, said friction member being adapted to move in relation to the wedge and casing, and a spring for yieldingly resisting this movement.

20. In draft rigging for railroad cars, the combination of a longitudinally and transversely movable friction element, a longitudinally movable friction element coacting 85 with the first mentioned element, means for holding the parts in operative engagement and a lever for imparting longitudinal motion to both of said elements in the same direction relative to the means for holding the parts in operative engagement.

21. In draft rigging for railroad cars, the combination of a draw-bar, lever mechanism, wedge mechanism composed of a plurality of 95 parts, said wedge mechanism adapted to have frictional engagement between its parts, a friction member, means for holding the parts in operative engagement, and a spring to yieldingly maintain the same in 100 operative position, the lever mechanism being adapted to cause the friction member and parts of the wedge mechanism to move in the same direction.

Signed at Montreal, Canada, this first day 105 of June, 1920.

WINFIELD H. YOST.
